UNITED STATES PATENT OFFICE.

HEBER C. PETERS, OF INDIANAPOLIS, INDIANA, ASSIGNOR TO BURROUGHS ADDING MACHINE COMPANY, OF DETROIT, MICHIGAN, A CORPORATION OF MICHIGAN.

ADDING-MACHINE.

1,094,012.

Specification of Letters Patent. Patented Apr. 21, 1914.

Application filed August 22, 1904. Serial No. 221,655.

To all whom it may concern:

Be it known that I, HEBER C. PETERS, a citizen of the United States, residing at Indianapolis, in the county of Marion and 5 State of Indiana, have invented certain new and useful Improvements in Adding-Machines, of which the following is a specification.

In the construction of adding machines 10 of the multiple key-bank type, most machines are constructed in such manner that a number can be written of an order equal to the number of banks of keys. Where it is desired, however, to print two or more columns 15 of figures of low order, it has been customary to build what has become known as a "split" machine, in which case the keyboard, and mechanism controlled thereby, is divided into distinct sections which can 20 have no effect one upon the other. In such machines, the construction has been practically mere duplication without means of combination.

An object of my present invention is to 25 provide a construction by means of which the recording of intermediate ciphers may be controlled whereby, in one position of adjustment the means for recording individual items become unified into a complete and co- 30 acting structure while in the position of adjustment said recording means will be operated as independent sections.

With a machine of the structure described, 35 it is desirable that the accumulating mechanism be under control, either automatically or by manually manipulated means in such manner that any desired series of numbers may be accumulated for a total, while other series of numbers will have no effect 40 upon the accumulating mechanism.

An object of my invention is, therefore, 45 to provide means by which the accumulating mechanism may be controlled, as to action or inaction.

The accompanying drawings illustrate my 50 invention as applied to that type of adding machines known as the Burroughs type, the fundamental construction thereof being fully disclosed more particularly in Burroughs Patents Nos. 504,963 and 505,078, issued on September 12, 1893.

Referring to the drawings Figure 1 is a side elevation of such a machine embodying my invention, with the supporting frame

shown in dotted lines; Fig. 2 is a vertical 55 section on line 2 2 of Fig. 3 of the printing section provided with an embodiment of my invention; Fig. 3 is a section on line 3 3 of Fig. 2; Fig. 4 a view similar to Fig. 2 with the parts in a different position of ad- 60 justment, and the section somewhat in front of the section plane of Fig. 2. Fig. 5 is a similar section showing a modification of the combination and splitting means; Fig. 6, a horizontal section on line 6 6 of Fig. 5; 65 Fig. 7 a side elevation on the scale of Fig. 1, only showing means for automatically controlling the splitting and combining mechanism by means of a movement of the paper carriage; Fig. 8 a rear elevation of the 70 parts shown in Fig. 7; and Fig. 9 is a detail.

It is to be understood that while I have shown my invention as applied to an adding machine of the Burroughs type, such illustration has been merely for convenience, and 75 that the invention is by no means to be limited to such a machine, means and methods for adapting my invention to other types of calculating machines being readily apparent.

In the drawings, 291 indicates vertically 80 reciprocable finger keys which are arranged in the rows or banks of 9 each to indicate units, tens, hundreds, etc., to any desired extent. Each of these keys operates upon a bell-crank lever 217 which in turn acts upon 85 a locking slide 214 which, when acted upon, is held in the position to which it is moved by a pawl 228. Each bell-crank lever 217 acts upon a stop wire 270 which in turn controls the subsequent movement of mechanism 90 for acting upon the adjacent wheel of the accumulator 916. The accumulator pins are carried by a swinging carriage 910 moved back and forth by a link 914 having in its forward end an open notch 914' which 95 engages the pin 910' of the accumulator carriage 910. Link 914 is pivoted to the lower arm of the T lever 913 which at the ends of its cross arm carries pins 913' and 913'' adapted to be engaged by the swinging 100 pawl 821 carried at the end of a lever 813, said lever being carried by the shaft 800. Link 914 is connected by a link 911 with the totaling key lever 227 and this key is connected by a link 226 with a lever 219 carrying a rod 202 adapted to act upon all of the pawls 228 so as to simultaneously release 105 the slides 214.

As is well known to those familiar with a Burroughs machine, the series of accumulator pinions 916, one for each denomination, are arranged to mesh with a corresponding series of sectors 610 carried at the forward ends of the type-carrying levers or sector bars 611 also corresponding in number to the number of denominations or banks of keys. The degree of movement or descent of the sectors 610 and the consequent degree of elevation of the rearward or type bearing end of the levers 611, is dependent upon the particular stop wires 270 of each bank or row of keys which may have been operated. Upon the initial movement of the handle or main operating shaft of the machine the accumulator pinions 916 are thrown or swung forwardly out of mesh with their sectors 610 by reason of the action of the pitman or link 914 upon the accumulator carriage or frame 910, which pitman or link is at this time moved forwardly longitudinally by the anti-clockwise oscillation of the lever 913 through the medium of the rocking lever 813 and its pawl or wipe plate 821. While the pinions are thus out of mesh, the sectors 610 corresponding to the denominations where keys have been operated now descend distances dependent upon the values of the keys operated but upon the return stroke of the operating handle the pinions are restored to mesh with their sectors by reason of the rearward movement of the pitman or link 914, with the result that the values of the keys operated are transferred to the pinions upon the return movement of the sectors. When a grand total is taken the total key is depressed with the result that the bell crank 227 is rocked downwardly and the link 911 is likewise depressed, causing the latter to so shift the position of the link 914 as to interfere with its usual functions, whereby the accumulator pinions are left in mesh with their sectors or racks 610 which are permitted to descend distances dependent upon the values of the respective pinions and to thereby permit the printing mechanism to print, as the total, the amount expressed by the accumulator pinions. If the total key is kept depressed throughout the full operation of the handle the total is a grand total and the machine will be cleared when the handle returns to normal position but in case the total key is released and permitted to ascend or return to normal position at the end of the forward stroke of the operating handle, the total printed will be a sub-total inasmuch as the sectors or racks 610 upon their ascent during the return stroke of the handle will be in mesh with the accumulator pinions and will restore the latter to the position of value formerly occupied by them before the sub-total was taken, that is to say the racks 610 will re-transfer to the pinions the

amounts which were by the latter transferred to the racks for the printing of the sub-total.

As hereinbefore stated the machine is provided with as many type-carrying levers 611 as there are banks of keys, and these levers are pivoted upon the shaft 600, each carrier being provided with a plurality of type carriers 618 adapted to be operated upon by the hammers 715 which in turn are each operated by a driver or lever 716. Each lever 716, at its free end, is provided with a point *v* adapted to be engaged by the shoulder *b* of the detent 717, Figs. 2 and 4. Each detent 717 is provided as shown in Fig. 3, with a heel portion *d*² and, with the exception of the detent corresponding to the units bank of keys, and also of such other intermediate banks of keys as may be desired, each of said detents is provided with a bent tail portion *d*' which overlaps the heel portion *d*² of the adjacent trigger representing the next lower order of value. Each detent 717 is also provided with a shoulder *b*' adapted to be engaged by one of a series of pawls 718, each of which is provided with a tail adapted to be brought into engagement with a shoulder *y*' formed upon the lower edge of the carrier 611, Figs. 2 and 4. The pawls 718 are pivoted upon a shaft 704 carried by a pair of arms 711. When a complete machine is desired, *i. e.*, one in which the operation of any key in any bank will cause the operation of the hammer 715 belonging to that bank, and also the hammers belonging to all of the lower banks, *i. e.*, to the right of the bank of the operated key, each detent 717 is provided with a bent tail *d*' which overhangs the heel *d*² of the detent to its right. If, however, a split machine is desired, *i. e.*, one in which the recording mechanism is divided into two or more distinct sections, the operation of the keys in the corresponding section not affecting in any manner the printing mechanism directly relating to another section, it has heretofore been customary to omit the bent tail *d*' of every detent relating to the right hand bank of each set of banks, thus preventing transmission from one set of detents to the other.

In the embodiment of my invention illustrated in the drawings, I have shown two different means by which the machine can be made either "split" or "complete" by providing mechanism which may be thrown into or out of action to serve as a transmitting element between the two sets of detents. In Figs. 2, 3, 4 and 7 this mechanism consists of the following parts: Instead of the usual pawl 718 relating to the first or left-hand bank of the right-hand set of banks in the machine I substitute therefor an exactly similar pawl 718^a which differs from the other merely in thickness. Arranged alongside of the pawl 718^a is a pawl 718^b

of substantially the same thickness and having its forward end of the same shape as the pawls 718 and 718^a, adapted to engage the shoulder *b'* of the adjacent detent 717. The 5 pawl 718^b differs from the pawl 718 and 718^a in that instead of being provided at its rear end with an upturned portion adapted to engage the shoulder *y'* of an adjacent carrier 611, it is provided with a down-turned 10 portion which carries a pin 718^{b'} and, instead of having its engaging end normally urged downward into position to engage the shoulder *b'* of the adjacent detent, as is the case with all of the pawls 718 and 718^a, the 15 engaging end of the pawl 718^b is normally urged upward to the position shown in Fig. 2, by a light spring 718^{b''}. Arranged in the path of movement of pin 718^{b'} is a cam finger 790 provided with an upper cam surface 791. This cam finger is normally held 20 upward by means of an arm 792 carried by a shaft 793, the arm 792 being connected with the cam finger by means of a light spring 794 which is attached to the arm 792 by means of a slotted connection, as shown, 25 for a purpose which will appear. Arranged beneath cam finger 790 in order to limit its lowest position is a stop 795. Attached to the outer end of shaft 793 is an operating 30 lever 296, Fig. 1, and to this lever is connected a key 297 which is projected upward through the key-board in convenient position for operation, and normally held upward by means of a spring 298. In operation 35 at this point if a key 211 in a bank in line with or to the left of the intermediate detent 717^a (which has no tail *d'*) be operated at will, upon operation of the operating handle cause the operation of detent 717 in 40 line therewith, and all of the detents 717 to the right thereof until the detent 717^a is reached, but this detent, because of the omission of its tail *d'*, does not transfer to the next detent, so that only the hammers up to 45 and including the hammer controlled by the detent 717^a will be operated, unless, of course, a key in a bank to the right of the detent 718^a has been operated. The operation of the key last mentioned, causes the 50 operation of the detent 717 in line therewith by reason of the fact that as the operating handle is moved, the carrier 611 relating to the bank of keys containing the operated key moves forward out of the line of movement of the rear end of the corresponding pawl 718^a, and thus permits this pawl to engage the alined detent 717 while all of the other pawls 718 are thrown upward to the position occupied by the pawl 718^a in 55 Fig. 4 by reason of the engagement of the rear ends of these pawls with the shoulders *y'* of the alined carriers 611, and the operation of the hammers 715 to the right of the thus operated detent 717 is due to the action 60 of the overlapping tails *d'*.

Pivoted upon shaft 600 between the two carriers 611 which relate respectively to the right-hand bank of the left-hand set of banks of keys, and the left-hand bank of the right-hand set of banks, is a plate 695 provided with a pin 696 which extends over all of the carriers 611 to the left of plate 695. The plate 695 is provided at its lower end with a finger 697 which when the carriers 611 are in their lowest and normal position 75 engages the forward or substantially vertical arm of the cam finger 790 and prevents it from dropping down into the path of movement of pin 718^{b'}.

If it is desired to make the machine complete and cause a transfer, the operator depresses key 297, whereupon shaft 793 is swung and arm 792 moved to the position shown in full lines in Figs. 2 and 4, whereupon the support of spring 794 on the cam finger 790 is released, and the cam finger will then be entirely supported by the finger 697 of plate 695. With the parts in this position, so soon as the operating lever is moved, all of the carriers 611 move upward 90 to the position shown in full lines in Fig. 4, and dotted lines in Fig. 2, and when in this position, the finger 697 will have moved to the position shown in dotted lines in Fig. 2, thus permitting the cam finger 790 to drop 95 slightly, but not sufficient to bring its top below the center of pin 718^{b'}. Continued movement of the operating lever swings arm 711, and thus draws the pawls 718, 718^a and 718^b to the right and brings all of the rear 100 ends of the pawls 718 and 718^a into engagement with the alined shoulders *y'*.

If none of the keys of any of the key-banks have been operated, all of the pawls 718 and 718^a will have their free ends 105 thrown upward by reason of engagement with the shoulders *y'*, and none of the detents 717 and 717^a will be engaged, and consequently none of the hammers 715 will be operated, the pin 718^{b'} of the pawl 718^b 110 passing under the free end of the cam finger 790. If any of the keys of the banks to the right of the "split" of the machine have been operated, the corresponding carriers 611 will be moved up out of the path of movement of the rear ends of the alined pawls 718 and 718^a, and the proper pawls will cause an engagement of the alined catches 717 and consequent operation of the hammer 715, the action being exactly the 115 same as in the machine illustrated in the patent already referred to, the cam-finger 790 being held up above the path of movement of the pin 718^{b'} by means of the plate 695. If, on the other hand, any one of the keys of any of the banks corresponding to the carriers 611 over which the pin 696 of plate 695 extends, have been operated the corresponding carrier 611 will be raised 120 above its zero position, and will carry the 125 130

plate 695 up far enough to retract finger 697 from cam-finger 790 and permit it to drop upon the rest 795 with its forward end below the center of pin 718^b so that when the pawls 718, 718^a and 718^b are moved to the right, pin 718^b will ride up over the cam 790, thus causing a depression of the free end of the pawl 718^b, and causing it to engage its detent 717, and thus cause the release of the corresponding hammer operating lever 716 and, by reason of the overlapping tails *d'* of all of the detents to the right thereof, will cause the successive release and operation of all of the hammers 715 to the right. With the arm 792 in the position shown in full lines in Figs. 2 and 4, therefore, the machine is capable of printing the intermediate zeros in a number equal in points to the total number of banks of keys. At any time, however, by swinging arm 792 to the position shown in dotted lines in Fig. 2, and thus supporting the cam-finger 790 out of the path of movement of the pin 718^b the machine may be "split" so as to enable the operator to write simultaneously two or more independent columns of numbers.

As hereinbefore referred to the arm 792 has an elongated slot in which the lower end of the spring 794 is loosely secured in such manner as to afford a little play between such arm and the spring. This arrangement is desirable in order that the spring shall not resist the action of the plate 695 in lifting the finger 790 when such action is required inasmuch as, in such event, the end of the spring slides freely in the slot which would not be the case if the opening in the arm 792 was not elongated. Moreover the spring constitutes a link between the cam 790 and the arm 792, such link being preferably flexible instead of a rigid link for if such latter link were used and the shaft 793 should be moved by the connecting mechanism during the time the parts are in the position illustrated in Fig. 4, it might result in an injury to the mechanism, owing to the pull of the arm 792 upon the cam finger 790 tending to throw its rearward end upwardly while under the pin 718^b. With the present construction, however, the spring 794 would, in such event, simply be elongated and the finger 790 would rise to its elevated position on the return of the parts to their normal position.

It will readily occur to any one skilled in this type of machines that many modifications of the construction just described may be made without departing from the spirit 60 of my invention. In Figs. 5 and 6, I have shown one of these modifications. In this construction, none of the pawls 718 are changed, but instead for the detent 717 which would ordinarily aline with the right-hand bank of keys at the line of "splitting"

of the machine, I substitute a detent 717^b which, instead of being provided with a tail *d'* overhanging the next adjacent detent 717, is provided with a sliding finger 717^c which is normally urged out of alinement with the heel *d*² of the next adjacent detent 717 by means of the light spring 717^d. The finger 717^c is preferably carried by a sliding carriage 717^e provided at its outer end with a pin 717^f adapted to be engaged by one arm 75 of a lever 790^a which is connected by a pin and slot connection with an arm 792^a carried by the shaft 793. The detent 717^b is then provided upon its left-hand side with a shoulder 717^g over which the tail *d'* of the 80 detent 717 to the left will project. The operation of this modification is readily apparent. With the parts in position shown in full lines in Figs. 5 and 6, an operation of the detent 717^b either by direct engagement by its own pawl 718, or by receiving actuation from the tail *d'* of the detent 717 to its left, will not affect the detent 717 to its right, for the reason that its pin 717^c will not engage the heel *d*² thereof. If, however, the parts be moved to the positions shown in dotted lines in Fig. 5, pin 717^c will automatically transfer to the detent 717 at its right.

It will be readily understood that the 95 mechanism for splitting and combining the machine may be operated automatically, either by successive movements of the operating lever, or by the operation of the movable paper carriage, without departing 100 from my invention. In Figs. 7 and 8 I have shown means for automatically operating the mechanism by a movable paper carriage. Here the shaft 793 is provided with a lever 50^a connected by a link 52 with a lever 54, 105 this last-mentioned lever 54 having an arm 54^a extended into the path of movement of a cam 55 adjustably arranged on a longitudinally slotted plate 55^a mounted upon the paper carriage 56. In this construction, the carriage carries a rock shaft 57 provided with a pawl 58 adapted to engage in any one of the series of notches formed in the stationary bar 59, whereby the carriage may be held in different columnar positions. Shaft 57 also carries one or more arms 60 which may be adjusted either in alinement with or in position to be brought into alinement with a pawl 61 carried by a lever 62, which lever is operated upon each operation 110 of the main operating lever by means of a lever 63, the arrangement being such that, upon each complete swing of the lever 63, the catch 58 will be withdrawn from one of the notches of bar 59, and then permitted 115 to be returned in engagement with the next notch of the bar 59 as the carriage is automatically shifted by the spring drum 64.

It will thus be understood that the mechanism which controls the split or combined 120

condition or character of the machine is itself under the control of the carriage whose position determines whether the machine is split or complete that is whether it is at any particular time split in sections or whether the machine is complete and capable of operation as an entirety. Moreover the arrangement is such that said mechanism may be moved or operated by the movable paper carriage at any particular position of the latter as predetermined by the operator, with the result that the machine may be automatically split or left complete according to the position of the paper carriage and according to any predetermined plan of the operator, under which arrangement some columns on a sheet of paper may represent the work of the complete machine and other columns may represent the work of the machine as split, the position of the carriage and consequently of the particular column with relation to the printing mechanism determining the particular condition of the machine when such column is printed. Thus when the carriage is in the particular position illustrated in Fig. 7, the arm or finger 54' which extends rearwardly in position to be operated upon by a projecting portion of the movable paper carriage, is in its inactive position but is interposed in the path of movement of the cam 55 and is arranged to be rocked downwardly by such cam when the latter is presented thereto. Inasmuch as the arm or finger 54' is in inactive position and as the normal condition of the machine is split, the machine is of course at this time split. When however the paper carriage moves longitudinally in advancing to the next columnar position, the cam will contact with the arm or finger 54' and depress the latter as indicated in Fig. 8 with the result that the link 52 is rocked upwardly and the shaft 793 and its arm 792 are rocked in a clockwise direction, Fig. 7, thereby rendering the machine complete by causing it to transfer or bridge across the line of split. When the paper carriage advances to the next columnar position, thereby carrying the cam beyond the arm or finger 54', the parts will be restored to the relative position indicated in Fig. 7 with the exception that such arm will be on the other side of the cam 55. The machine is now again in split condition. By adjustably mounting the cam 55 in the slotted plate 55' as before mentioned, the machine may be rendered split or complete for the different columns on a sheet of paper as determined by location of the cam. In this manner different characters of accountant work may be readily provided for so that the machine may be split or complete according to the particular position of the paper carriage and without any attention on the part of the operator.

The machine thus far described is designed to enable the operator to write upon the same page several columns of numbers. With such a machine, it is convenient to provide means for preventing the operation of the accumulator at times, and the apparatus already described may, therefore, be combined with some means for controlling the accomplishment of function of the accumulator. If desired, mechanism such as hereinafter described, may be used, or any other suitable mechanism for controlling the accomplishment of function of the accumulator. In the present drawings I indicate briefly the means for shifting the accumulator which means *per se* form no part of my present invention.

The lever 54^a, (Fig. 1) exactly like lever 54 shown in Fig. 7, is connected by a link 54^a to a lever 54^b pivoted upon shaft 600. Lever 54^b is provided at one end with a finger 54^c adapted to engage a pin 828' carried by latch 828 and thus prevent it from locking lever 227. Lever 54^b carries a depending link 54^b provided at its lower end with a pin 54^c adapted, when in its lower position, to be engaged by a lug 813' carried by lever 813, and to then engage a lever 65 pivoted on shaft 800. The lever 65 is provided at its upper end with a notch which receives a pin 226' carried by link 226.

In operation, the lever 54^a is normally held in the position shown in full lines in Fig. 1 by a spring 54'. When lever 813 is moved to the left its lug 813' engages pin 54^c and drives it against lever 65, whereupon link 226 pulls upon lever 227 which drops and permits link 911 and link 914 to drop until the upper rear edge of notch 914' drops below the center of pin 910'. Link 914 is pulled by the spring 911' away from pin 910' and thus leaves the accumulator 916 out of accumulating position. By depressing the left-hand end of lever 54^a by cam 55 pin 54^c is withdrawn from between lug 913' and lever 65 so that the function of link 914, and consequently of the accumulator is not interfered with. Thus the accumulating mechanism is under the control of the paper carriage whose position determines whether such mechanism is operative or inoperative. According to the construction shown in Fig. 1 the controlling mechanism, that is the lever 54^a and its associated parts, is in position to normally interfere with the accumulating mechanism and render the same inoperative inasmuch as normally the pin 54^c is in a position to form an operating connection between the block or lug 913' and the substantially vertical lever 65, with the result that when the machine is operated with the controlling mechanism in normal condition, the lever 65 will be rocked rearwardly and the link 226 moved rearwardly and the total key bell 130

crank 227 rocked downwardly slightly so as to place, through the medium of the link 911, the pitman or link 914 in an inoperative position, which is intermediate its normal 5 or its upper position as shown in Fig. 1 and its lower position to which it is shifted or depressed in the operation of taking a total. When the pitman or link is in such intermediate position, it can no longer control 10 the swinging of the accumulator pinions in the manner hereinbefore explained, but after such pinions have been swung forwardly out of mesh with their racks upon the initial or forward stroke of the operating handle, 15 such pinions are left out of mesh upon the return stroke inasmuch as the pitman 914 which has heretofore served to so return them upon the rearward or return stroke of the operating handle is in its inoperative or 20 intermediate position. The result is that the racks 610 descend and then ascend while the accumulator pinions are out of mesh, with the result that the movements of such racks or sectors are not transferred to the 25 accumulator pinions, or in other words, the accumulating mechanism is at this time inoperative and the machine is simply performing its function of printing. When however the paper carriage advances to the 30 next columnar position the cam 55 will depress the arm or finger 54' and rock the lever 54^a in such a manner as to raise the interfering pin 54^c to a position beyond the path of movement of the lug or block 813', 35 with the result that the machine, as to its accumulating mechanism, will print as a regular standard Burroughs machine inasmuch as the rocking of the lever 813 will have no effect whatever upon the lever 65 40 so that the accumulator pinions will be controlled by the pitman or link 914 in the usual and well-known way. Therefore in this particular position of the paper carriage the accumulating mechanism will be 45 in operative condition and the items in the particular column now being listed will be accumulated by the machine. The provision of a plurality of cams 55 and their adjustment or location in the slotted plate 55', 50 in the manner hereinbefore explained, will permit different columns of items to be printed on the same sheet of paper some of which columns represent accumulated items and others items which have simply been printed 55 without accumulation, the order and arrangement of the accumulated and non-accumulated columns being according to the prearranged plan of the cams 55. It is understood however that the feature of so controlling the accumulating mechanism does 60 not, *per se*, form any part of my present invention inasmuch as I have made it the subject matter of an application heretofore filed by me (May 12, 1904, Serial No. 207,631, 65 now Patent No. 1,028,133 issued June 4,

1912), and I herein claim this feature only as an element in some of the claims, in a combination including the means for controlling the split and complete conditions of the machine whereby a number of columns of items may be simultaneously printed with a single machine and whereby the machine may print some of the columns on the sheet of paper without accumulating the items thereof. 70

In some of the claims which follow the term "accounting devices" is employed to designate broadly the means whereby denominational individual registration or recording or both is done. 75

I claim as my invention: 80

1. In a multiple key-bank adding machine, having a longitudinally movable paper carriage, a plurality of accounting devices controlled by the key-banks respectively and co-operatively related, and means controlled by said carriage for rendering the machine either split or complete through control of co-operative relationship between the said accounting devices. 85

2. In a multiple key-bank adding machine, having a longitudinally movable paper carriage, a plurality of accounting devices controlled by the key-banks respectively and co-operatively related, and means for rendering the machine either split or complete according to the position of the carriage through control of co-operative relationship between the said accounting devices. 90

3. In a multiple key-bank adding machine, having a longitudinally movable paper carriage, a plurality of accounting devices controlled by the key-banks respectively and co-operatively related, and means controlled both manually and by the paper carriage for rendering the machine either split or complete through control of co-operative relationship between the said accounting devices. 100

4. In a multiple key-bank adding machine, having a longitudinally movable paper carriage, a plurality of accounting devices controlled by the key-banks respectively and co-operatively related, and means for rendering the machine either split or complete according to the position of the carriage as predetermined by the operator through control of co-operative relationship between the said accounting devices. 110

5. In a multiple key-bank adding machine, a plurality of accounting devices controlled by the key-banks respectively and co-operatively related, the machine being normally split through non-cooperative relationship of certain of said accounting devices, and provided with a movable paper carriage, and means under the control of said carriage for making the machine complete through establishment of co-operative relationship of said accounting devices. 120

6. In a multiple key-bank adding machine which is normally split and provided with a movable paper carriage, means for making the machine complete according to the position of the carriage. 5
7. In a multiple key-bank adding machine which is normally split and provided with a movable paper carriage, means for making the machine complete, said means being under the control of the paper carriage at any particular position thereof, as predetermined by the operator, said means being actuated to make the machine complete. 10
8. In an adding machine having printing mechanism arranged to automatically print ciphers in the denominational columns in which no key has been operated, and means governed by the operator for controlling such printing of ciphers whereby ciphers intermediate digits may be printed or omitted according to a predetermined plan. 15
9. In an adding machine, mechanism adapted to print a plurality of figures at one operation, a paper carriage coöperating with said printing mechanism, and means for separating or combining the printing mechanism, whereby separate amounts or a single amount may be printed at one operation. 20
10. In an adding machine, printing mechanism capable of printing a plurality of figures at one operation, means for predetermineding the character and position of the figures printed at each operation, means for separating or combining said printing mechanism to cause its operation in independent sections or as a unit, respectively, a paper carriage coöperating with said printing mechanism, and means for shifting the printing mechanism and paper carriage relatively to different columnar positions. 25
11. In an adding machine, printing mechanism capable of printing a plurality of figures at one operation, means for predetermineding the character and position of figures printed at each operation, means for separating or combining said printing mechanism to cause its operation in independent sections or as a unit, respectively, a paper carriage coöperating with said printing mechanism, means for shifting the printing mechanism and paper carriage relatively to different columnar positions, an accumulating mechanism, and means for eliminating the function of said accumulating mechanism. 30
12. In an adding machine, printing mechanism capable of printing a plurality of figures at one operation, means for predetermineding the character and position of figures printed at each operation, means for separating or combining said printing mechanism to cause its operation in independent sections or as a unit, respectively, a paper carriage coöperating with said printing mechanism, means for shifting the printing 35
- mechanism and paper carriage relatively to different columnar positions, an accumulating mechanism, and means for bringing said accumulating mechanism into accumulating correlation with the printing mechanism in one columnar position, and for withdrawing said accumulating mechanism from accumulating correlation in another columnar position. 40
13. In an adding machine, recording mechanism capable of recording a plurality of figures at one operation, means for predetermineding the character and position of figures recorded at each operation, means for separating or combining said recording mechanism to cause its operation in independent sections or as a unit, and means for recording in different columnar positions with provisions for controlling the last-mentioned means accordingly. 45
14. In an adding machine, recording mechanism capable of recording a plurality of figures at one operation, means for predetermineding the character and position of figures recorded at each operation, means for separating or combining said recording mechanism to cause its operation in independent sections or as a unit, means for recording in different columnar positions, an accumulating mechanism, and means for eliminating the function of said accumulating mechanism. 50
15. In an adding machine, recording mechanism capable of recording a plurality of figures at one operation, means for predetermineding the character and position of figures recorded at each operation, means for separating or combining said recording mechanism to cause its operation in independent sections or as a unit, means for recording in different columnar positions, an accumulating mechanism, and means for bringing said accumulating mechanism into or out of accumulating correlation with the recording mechanism in different columnar 55
- positions. 60
16. In an adding machine of the multiple key-bank type, recording mechanism capable of recording a plurality of figures at one operation, means controlled by the multiple key-banks for predetermineding the character and position of recorded figures, means for recording sets of figures in different columnar positions, and means for separating or combining the recording 65
- means to cause its operation in independent sections or as a unit. 70
17. In an adding machine of the multiple key-bank type, recording mechanism capable of recording a plurality of figures at one operation, means controlled by the multiple key-banks for predetermineding the character and position of recorded figures, means for recording sets of figures in different columnar positions, means for sepa- 75

- rating or combining the recording means to cause its operation in independent sections or as a unit, accumulating mechanism, and means for eliminating the accumulating function thereof.
18. In an adding machine of the multiple key-bank type, recording mechanism capable of recording a plurality of figures at one operation, means controlled by the multiple key-banks for predetermining the character and position of recorded figures, means for recording sets of figures in different columnar positions, means for separating or combining the recording means to cause its operation in independent sections or as a unit, accumulating mechanism, and means for eliminating the accumulating function thereof in different columnar recording positions.
19. In an adding machine of the multiple key-bank type, recording mechanism, means controlled by the key-banks for predetermining the position and character of recorded figures, means for recording in different columnar positions, transferring means between the key-banks and the recording means for automatically recording necessary zeros to the right of the operated key of highest order in each operation, and means for controlling the range of action of such transferring means according to the columnar condition of the recording means.
20. In an adding machine of the multiple key-bank type, recording mechanism, means controlled by the key-banks for predetermining the value position and character of recorded figures, means for recording in different columnar positions, transferring means between the key-banks and the recording means for automatically recording necessary zeros to the right of the operated key of highest order in each operation, means for controlling the range of action of such transferring means, an accumulator, and means for eliminating the accumulating function thereof.
21. In an adding machine of the multiple key-bank type, recording mechanism, means controlled by the key-banks for predetermining the value position and character of recorded figures, means for recording in different columnar positions, transferring means between the key-banks and the recording means for automatically recording necessary zeros to the right of the operated key of highest order in each operation, means for controlling the action or non-action of such transferring means in line with an intermediate key-bank, an accumulator, and means for eliminating the accumulating function thereof in one or more columnar recording positions.
22. In an adding machine, recording mechanism capable of recording a plurality of figures at one operation, means for determining the character and value position of figures recorded, transferring means between said predetermining means and the recording means for automatically recording necessary zeros to the right of the operated predetermining means of highest order in each operation, means for recording in different columnar positions, and means for controlling the action or non-action of the transferring means in line with an intermediate portion of the recording means and as governed by the columnar condition of the recording means.
23. In an adding machine, recording means capable of recording a plurality of figures at one operation, means for predetermining the position and character of recorded figures, means for automatically recording the necessary zeros to the right of the operated predetermining means of highest order for each operation, means for recording in different columnar positions, a single means for controlling the range of action of the zero recording means, an accumulator, and means for eliminating the accumulating function thereof in one or more columnar recording positions.
24. In an adding machine, recording means capable of recording a plurality of figures at one operation, means for predetermining the position and character of recorded figures, means for automatically recording the necessary zeros to the right of the operated predetermining means of highest order for each operation, means for recording in different columnar positions, a single means for controlling the range of action of the zero recording means up to and from an intermediate order of value, an accumulator, and means for eliminating the accumulating function thereof in one or more columnar recording positions.
25. In an adding machine of the multiple key-bank type, recording means capable of recording a plurality of figures at one operation, means controlled by the multiple key-banks for predetermining the position and character of recorded figures, means for automatically recording the necessary zeros to the right of the operated key-bank of highest order, means for recording in different columnar positions, a single means for controlling the range of action of said zero-recording means, an accumulator, and means for eliminating the accumulating function thereof.
26. In an adding machine of the multiple key-bank type, recording means capable of recording a plurality of figures at one operation, means controlled by the multiple key-banks for predetermining the position and character of recorded figures, means for automatically recording the necessary zeros to the right of the operated key-bank of highest order, means for recording in differ-

- ent columnar positions, a single means for controlling the range of action of said zero recording means up to and from an intermediate order of value, an accumulator, and 5 means for eliminating the accumulating function thereof in one or more columnar recording positions. 27. In an adding machine, recording means capable of recording a plurality of figures at one operation, means for predetermining the value position and character of recorded figures, means for automatically recording intermediate zeros, means for recording in different columnar positions, and 10 means for controlling the range of action of said zero-recording means according to the columnar condition of the recording means. 28. In an adding machine, recording means capable of recording a plurality of figures at one operation, means for predetermining the value position and character of recorded figures, means for automatically recording intermediate zeros, means for recording in different columnar positions, and 15 means for permitting or preventing the operation of said zero recording means from an intermediate value position toward the right to the next value to be recorded according to the columnar condition of the recording 20 means. 29. In an adding machine, recording means capable of recording a plurality of figures at one operation, means for predetermining the value position and character of recorded figures, means for automatically recording intermediate zeros, means for recording in different columnar positions, means for controlling the range of action of said zero-recording means, an accumulator, 25 and means for eliminating the accumulating function thereof. 30. In an adding machine, recording means capable of recording a plurality of figures at one operation, means for predetermining the value position and character of recorded figures, means for automatically recording intermediate zeros, means for recording in different columnar positions, means for permitting or preventing the operation of said zero-recording means from an intermediate value position toward the right to the next value to be recorded, an accumulator, and means for eliminating the accumulating 30 function thereof. 31. In an adding machine of the multiple key-bank type, recording means capable of recording a plurality of figures at one operation, means controlled by the multiple key-banks for predetermining the character and position of recorded figures at each operation, means for automatically recording intermediate zeros, means for recording in different columnar positions, and means for controlling the range of action of the zero-recording means up to and from an intermediate order of value, an accumulator, and 35 means for eliminating the accumulating function thereof in one or more columnar recording positions. 32. In an adding machine of the multiple key-bank type, recording means capable of recording a plurality of figures at one operation, means controlled by the multiple key-banks for predetermining the character and position of recorded figures at each operation, means for automatically recording intermediate zeros, means for recording in different columnar positions, and means for permitting or preventing the operation of the zero-recording means from an intermediate value position toward the right to the next value to be recorded at such operation according to the columnar condition of the recording means. 33. In an adding machine of the multiple key-bank type, recording means capable of recording a plurality of figures at one operation, means controlled by the multiple key-banks for predetermining the character and position of recorded figures at each operation, means for automatically recording intermediate zeros, means for recording in different columnar positions, means for controlling the range of action of the zero-recording means, an accumulator, and means for eliminating the accumulating function thereof. 34. In an adding machine of the multiple key-bank type, recording means capable of recording a plurality of figures at one operation, means controlled by the multiple key-banks for predetermining the character and position of recorded figures at each operation, means for automatically recording intermediate zeros, means for recording in different columnar positions, means for permitting or preventing the operation of the zero-recording means from an intermediate value position toward the right to the next value to be recorded at such operation, an accumulator, and means for eliminating the accumulating function thereof in one or more columnar recording positions. 35. In an adding machine, a plurality of sets of impression means by which a plurality of figures may be recorded at a single operation, predetermining means for controlling the value recording positions of said sets of impression means, a plurality of individual actuators, one for each set of impression means, transferring means for automatically operating actuators to the right of the actuator controlled by any operated portion of the predetermining means, means for varying the range of action of said transferring means, and means for operating said impression means in different columnar positions and correspondingly controlling said varying means. 36. In an adding machine, a plurality of sets of impression means by which a plurality of figures may be recorded at a single operation, predetermining means for controlling the range of action of said zero recording means up to and from an intermediate order of value, an accumulator, and means for eliminating the accumulating function thereof in one or more columnar recording positions.

- trolling the value recording position of said sets of impression means, a plurality of individual actuators, one for each set of impression means, transferring means for automatically operating actuators to the right of the actuator controlled by any operated portion of the predetermining means, means for varying the range of action of said transferring means, means for operating said impression means in different columnar positions, an accumulator, and means for eliminating the function of said accumulator.
37. In an adding machine of the multiple key-bank type, a plurality of sets of impression means, a plurality of banks of value keys each bank for predetermining the value position of its set of impression means, a plurality of actuators one for each set of impression means, transferring means for automatically operating the actuators to the right of any operated actuator, means for varying the range of action of said transferring means, and means for recording in different columnar positions and correspondingly controlling said varying means.
38. In an adding machine of the multiple key-bank type, a plurality of sets of impression means, a plurality of banks of value keys each bank for predetermining the value position of its set of impression means, a plurality of actuators one for each set of impression means, a plurality of actuators one for each set of impression means, transferring means for automatically operating the actuators to the right of any operated actuator, means for varying the range of action of said transferring means, means for recording in different columnar positions, an accumulator, and means for eliminating the accumulating function thereof.
39. In an adding machine of the multiple key-bank type, a plurality of sets of impression means, a plurality of banks of value keys each bank for predetermining the value position of its set of impression means, a plurality of actuators one for each set of impression means, transferring means for automatically operating the actuators to the right of any operated actuator, means for varying the range of action of said transferring means, means for recording in different columnar positions, an accumulator, and means for eliminating the accumulating function thereof in one or more columnar recording positions.
40. In an adding machine, a plurality of sets of impression means capable of recording a plurality of figures at one operation, means for predetermining the value-recording positions of said impression means, means for actuating said impression means, means for automatically bringing non-predetermined impression means to zero-recording position, means for varying the range of action of the actuating means upon

said zero-recording impression means, and means for recording in different columnar positions and accordingly controlling the aforesaid varying means.

41. In an adding machine, a plurality of sets of impression means capable of recording a plurality of figures at one operation, means for predetermining the value-recording positions of said impression means, means for actuating said impression means, means for automatically bringing non-predetermined impression means to zero-recording position, means for varying the range of action of the actuating means upon said zero-recording impression means, means for recording in different columnar positions, an accumulator, and means for eliminating the accumulating function thereof.

42. In an adding machine, a plurality of sets of impression means capable of recording a plurality of figures at one operation, means for predetermining the value-recording positions of said impression means, means for actuating said impression means, means for automatically bringing non-predetermined impression means to zero-recording position, means for varying the range of action of the actuating means upon said zero-recording impression means, means for recording in different columnar positions, an accumulator, and means for eliminating the accumulating function thereof in one or more columnar recording positions.

43. In an adding machine, the combination with a plurality of sets of impression means and means for predetermining the recording positions thereof at any operation, of a plurality of actuators, one for each set of impression means, a plurality of detents each normally restraining one of said actuators, interacting portions between said detents dividing the same into two groups, whereby the detents to the right of any operated detent in each group will be automatically operated thereby, a series of pawls controlled by the position of the impression means for actuating said detents, a second pawl arranged in conjunction with the left hand detent of the right hand set and normally in inactive position, and means controlled by the operation of the predetermining means of the left-hand set for automatically causing action of said second pawl upon its detent.

44. In an adding machine, the combination with a plurality of sets of impression means and means for predetermining the recording positions thereof at any operation, of a plurality of actuators, one for each set of impression means, a plurality of detents each normally restraining one of said actuators, interacting portions between said detents dividing the same into two groups, whereby the detents to the right of any operated detent in each group will be automatically

5 cally operated thereby, a series of pawls controlled by the position of the impression means for actuating said detents, a second pawl arranged in conjunction with the left-hand detent of the right hand set and normally in inactive position, a cam finger adapted to be moved into the path of movement of said pawl to throw the same into active coöperation with its detent, means for holding said pawl in inactive position, and means controlled by the position of the impression means belonging to the left-hand set of detents for finally determining the active or inactive position of said cam finger.

10 45. In an adding machine, the combination of, a plurality of sets of figure-types, each set ranging from 0 to 9 inclusive, a paper carriage coöperating therewith, means for selecting and bringing any figure of 20 value in any set to printing position at will, a plurality of actuators, one coöperating with each set of type, means for selectively operating the actuator which coöperates with any type-set in which a figure of value 25 has been brought to printing position, means for automatically operating the actuators coöperating with the non-selected type-sets to the right of the selected type-set of highest order, and means for varying the range of 30 action of said automatic-actuator-operating means with relation to an intermediate type-set.

35 46. In an adding machine, the combination of, a plurality of sets of figure-types, each set ranging from 0 to 9 inclusive, a paper carriage coöperating therewith, means for selecting and bringing any figure of value in any set to printing position at will, a plurality of actuators, one coöperating 40 with each set of type, means for selectively operating the actuator which coöperates with any type-set in which a figure of value has been brought to printing position, means for automatically operating the actuators coöperating 45 with the non-selected type-sets to the right of the selected type-set of highest order, means for varying the range of action of said automatic-actuator-operating means with relation to an intermediate type-set, 50 and means for recording in different columnar positions.

55 47. In an adding machine, the combination of, a plurality of sets of figure-types, each set ranging from 0 to 9 inclusive, a paper carriage coöperating therewith, means for selecting and bringing any figure of value in any set to printing position at will, a plurality of actuators, one coöperating 60 with each set of type, means for selectively operating the actuator which coöperates with any type-set in which a figure of value has been brought to printing position, means for automatically operating the actuators coöperating 65 with the non-selected type-sets to the right of the selected type-set of highest

order, means for varying the range of action of said automatic-actuator-operating means with relation to an intermediate type-set, means for recording in different columnar positions, an accumulator, and means for eliminating the accumulating function thereof. 70

48. In an adding machine, the combination of, a plurality of sets of figure-types, each set ranging from 0 to 9 inclusive, a paper carriage coöperating therewith, means for selecting and bringing any figure of value in any set to printing position at will, a plurality of actuators, one coöperating with each set of type, means for selectively operating the actuator which coöperates with any type-set in which a figure of value has been brought to printing position, means for automatically operating the actuators coöperating with the non-selected type-sets to the 85 right of the selected type-set of highest order, means for varying the range of action of said automatic-actuator-operating means with relation to an intermediate type-set, means for recording in different columnar positions, an accumulator, and means for eliminating the accumulating function thereof in one or more columnar recording positions. 90

49. In a multiple key-bank machine, the combination, with the accumulating mechanism, of means for rendering such mechanism operative or inoperative, recording mechanism with elements coöperatively related for cipher printing and means for rendering the same either split or complete at the will of the operator. 95

50. In a multiple key-bank machine, the combination, with the accumulating mechanism, of a movable paper carriage, means under the control of the carriage for rendering the accumulating mechanism operative or inoperative according to the position of such carriage, recording mechanism with elements coöperatively related 105 for cipher printing and means for rendering the same either split or complete at the will of the operator. 110

51. In a multiple key-bank machine, the combination, with the accumulating mechanism, of a movable paper carriage, means normally rendering the accumulating mechanism inoperative but controlled by the carriage to permit the operation of the mechanism according to the position of the carriage, recording mechanism with elements coöperatively related for cipher printing and means for rendering the same either split or complete at the will of the operator. 115 120

52. In a multiple key-bank machine, the combination, with the accumulating mechanism, of a movable paper carriage, means controlled by the carriage for rendering the accumulating mechanism inoperative, recording mechanism with elements coöpera- 125 130

tively related for cipher printing and key controlled means for controlling the split or complete condition of the same.

53. In a multiple key-bank machine, the combination, with the accumulating mechanism, and with printing mechanism which is normally split, of a movable paper carriage, means controlled by the carriage for rendering the accumulating mechanism inoperative, and means under the control of the operator for changing the printing mechanism from split to complete condition.

54. In a multiple key-bank machine, the combination, with the accumulating mechanism, and with printing mechanism which is normally split, of a movable paper carriage, means controlled by the carriage for rendering the accumulating mechanism inoperative, and key controlled means for changing the printing mechanism from split to complete condition.

55. In a multiple key-bank machine, the combination, with the accumulating mechanism, and with printing mechanism which is normally split, of a movable paper carriage, means controlled by the carriage for rendering the accumulating mechanism inoperative, a device operating to eliminate the function of the accumulating mechanism, means adjustably mounted on the paper carriage for controlling said device and thereby determining whether the same shall be operative or inoperative at any particular time according to the particular adjustment, and means for changing the printing mechanism from split to complete condition.

56. In a machine of the character described, the combination of hammers, de-

tents for severally restraining the same, and detent disabling means comprising separate devices one for each detent with provisions for either individually or collectively disabling the detents, said disabling means including optionally operable pivotal instrumentalities for causing coördinate disablement of adjacent detents.

57. In a machine of the character described, the combination of hammers, detents for severally restraining the same, and detent disabling means comprising separate devices one for each detent with provisions for either individually or collectively disabling the detents, said disabling means including optionally operable instrumentalities for causing coördinate disablement of adjacent detents and said instrumentalities including a pivoted piece or pawl and a key and connections for controlling the same.

58. In a machine of the class described, the combination with a prime mover and recording mechanism comprising individual elements coöperatively related for cipher-printing with provisions for suspending the coöperative relationship between sections of said elements, of means for automatically effecting the suspension through operation of the prime mover.

In witness whereof, I, have hereunto set my hand and seal at Indianapolis, Indiana, this 18 day of August, A. D. one thousand nine hundred and four.

HEBER C. PETERS. [L. S.]

Witnesses:
